[57] CLAIM

The ornamental design for a spring support for ski seat or similar article, as shown and described.

DESCRIPTION

FIG. 1 is a perspective view of a spring support for ski seat or similar article showing our new design;
FIG. 2 is a right side elevational view thereof, the left side elevational view being a mirror image;
FIG. 3 is a top plan view thereof;
FIG. 4 is a bottom plan view thereof;
FIG. 5 is a front elevational view thereof; and,
FIG. 6 is a rear elevational view thereof.
The broken lines showing a ski and a seat in the drawings represent environment only and form no part of the claimed design.
